(57) **CLAIM**

The ornamental design for a removable vehicle seat headrest cover, as shown and described.

DESCRIPTION

FIG. 1 is a front elevated view of a removable vehicle seat headrest cover showing my new design.

FIG. 2 is a rear elevated view of the removable vehicle seat headrest cover.

FIG. 3 is a side elevated view of the removable vehicle seat headrest cover.

FIG. 4 is a top plan view of the removable vehicle seat headrest cover.

FIG. 5 is a bottom plan view of the removable vehicle seat headrest cover; and,

FIG. 6 is a perspective view of the removable vehicle seat headrest cover.

The broken line showing of a name, in FIGS. 1 and 2, and a seat and support, in FIG. 6, is for illustrative purposes only and forms no part of the claimed design.
